Primary Examiner — Eric L Good*Assistant Examiner* — Sanjeev Paul(57) **CLAIM**

The ornamental design for a wedge cushion, as shown and described.

DESCRIPTION

FIG. 1 is an oblique perspective view of a wedge cushion showing my new design.

FIG. 2 is a top aerial perspective view of the wedge cushion thereof.

FIG. 3 is an end perspective view of the wedge cushion thereof.

FIG. 4 is a front perspective view of the wedge cushion thereof; and,

FIG. 5 is the rear perspective view of the wedge cushion thereof.

1 Claim, 5 Drawing Sheets(56)
